Filed Apr. 8, 1959, Ser. No. 55,413

Term of patent 14 years

(Cl. D34—5)

FIG.1.

FIG.2.

FIG.3.

Figure 1 is a front elevational view of a stilt showing my new design;

Figure 2 is a side elevational view thereof; and

Figure 3 is a top plan view thereof.

My design comprises a stilt having bends throughout its length and having the lower or foot-receiving portion thereof twisted at a 90° angle to the upper or arm and hand-receiving portion, substantially as shown.

I claim:

The ornamental design for a stilt, as shown and described.
